(57) **CLAIM**

An ornamental design for an earphone, as shown and described.

DESCRIPTION

FIG. 1 is an isometric view of the earphone design having mirror image right and left earphone earpieces;

FIG. 2 is a right side view of the right earphone earpiece; the left earphone earpiece is a mirror image of the right earpiece;

FIG. 3 is a front view of the right earphone earpiece; the left earphone earpiece is a mirror image of the right earpiece;

FIG. 4 is a rear side view of the right earphone earpiece; the left earphone earpiece is a mirror image of the right earpiece;

FIG. 5 is a left view of the right earphone earpiece; the left earphone earpiece is a mirror image of the right earpiece;

FIG. 6 is a front view of the right earphone earpiece; the left earphone earpiece is a mirror image of the right earpiece; and,

FIG. 7 is a bottom view of the right earphone earpiece; the left earphone earpiece is a mirror image of the right earpiece.

The broken lines in FIGS. 1 through 6 is for illustrative purposes only and forms no part of the claimed design.
